UNITED STATES PATENT OFFICE.

AUGUST SUNDH, OF YONKERS, NEW YORK, ASSIGNOR TO OTIS ELEVATOR COMPANY, OF JERSEY CITY, NEW JERSEY, A CORPORATION OF NEW JERSEY.

POWER TRANSMITTING AND CONTROLLING MECHANISM.

1,134,770.

Specification of Letters Patent.

Patented Apr. 6, 1915.

Application filed February 13, 1909. Serial No. 477,748.

To all whom it may concern:

Be it known that I, AUGUST SUNDH, a citizen of the United States, residing at Yonkers, in the county of Westchester and State 5 of New York, have invented a new and useful Improvement in Power Transmitting and Controlling Mechanisms, of which the following is a specification.

The present invention relates to fluid 10 power transmitting and controlling mechanism, and, as herein shown, is particularly adapted for use on automobiles.

The invention comprehends the use of a prime mover, a multiple fluid pressure system 15 operated thereby, and a hydraulic motor operated by the fluid pressure and adapted to be driven either at a slow speed by fluid supplied at high pressure, or at high speed with a larger volume of fluid supplied at a 20 low pressure, the horse-power output of the prime mover remaining practically constant.

The invention further comprises means whereby a variation of the speed and torque 25 of the hydraulic motor is obtained by a corresponding variation in the pressure and quantity of fluid supplied by the pumping system.

The invention comprises a multiple pressure system in which great variation in the 30 speed and power may be obtained by varying the combinations of the pumping units, and a suitable motor or motors driven thereby and adapted to operate an automobile.

The invention further consists of combinations and arrangements whereby the speed and power of the hydraulic motor may be regulated, and whereby the speed of the 40 prime mover may be increased after the hydraulic motor has attained its highest speed, means being provided for disengaging the hydraulic motor from the driven mechanism and operating the latter directly 45 by the prime mover.

One of the principal objects of the invention is the provision of means for utilizing the horse-power output of a gasoline engine, or other motor, to the best advantage, and to provide, in combination with the prime mover, fluid transmission mechanism whereby the speed can be changed from a minimum to a maximum, and the force varied from a maximum to a minimum,

or vice versa, while substantially the full 55 horse-power output is utilized at all times.

A still further object of the invention is to make it practicable to use high speed pumps with such mechanism, and particularly pumps which operate at a comparatively 60 low pressure, and by suitable valve mechanism may be arranged either to deliver a large quantity of fluid at a low pressure, or a small quantity under a high pressure, and at the same time keep the horse- 65 power output of the prime mover practically constant.

A further object of the invention is to provide means whereby when the driven machinery is stopped a minimum of power 70 is required to keep the gasoline engine or other prime mover and the pumps in motion.

The invention further aims to provide 75 simplicity in construction, so that the services of skilled mechanics are not required to operate the same, and to also secure durability and safety.

The invention further consists in novel arrangements of parts and combinations of 80 elements as set forth in the accompanying claims.

Referring to the drawings, Figure 1 is a plan view of an automobile truck with one form of the present invention applied thereto; Fig. 2 is an elevation of the same taken on the line 2—2 of Fig. 1, the rear portion of the truck being broken away; Fig. 3 is a detail view showing the valve controlling the supply of fuel to the engine, 85 and mechanism for operating and controlling said valve; Fig. 4 is a detail section taken on the line 4—4 of Fig. 2; Fig. 5 is a sectional plan view of the clutch mechanism; Fig. 6 is a sectional view taken on the 90 line 6—6 of Fig. 5; Fig. 7 is a sectional plan view of the pumping system; Fig. 8 is a sectional elevation taken on the line 8—8 of Fig. 7; Fig. 9 is an elevation view showing 95 a train of gearing for controlling the valves of the pumping system, the clutch, and the valve shown in Fig. 3; Fig. 10 is a part sectional elevation showing the hydraulic motors; Fig. 11 is a sectional view taken on the line 11—11 of Fig. 10; Fig. 12 is a section 100 taken on the line 12—12 of Fig. 10; Fig. 13 is a section taken on the line 13—13 of Fig. 12; Fig. 14 is a sectional detail elevation

view of the reversing valve; Fig. 15 is a sectional plan view of the valves controlling the pumps, the parts being in the position assumed when the engine is at rest; Figs. 16 to 20, inclusive, are similar views showing the successive positions which the valves take as the speed is being increased; Fig. 21 is a view similar to Fig. 7 of a modification; Fig. 22 is a sectional elevation of the pumping mechanism shown in Fig. 21; Fig. 23 is an elevation view of the gearing shown in Fig. 21; Figs. 24, 25 and 26 are views of another modification, and correspond respectively to Figs. 21, 22 and 23.

15 The general arrangement of parts as shown in Figs. 1 and 2, comprises a gasoline engine or other prime mover E mounted on the frame A of an automobile truck; a pumping system P connected to the engine E and comprising a plurality of pumps; a motor or motors M adapted to be operated by fluid pressure from the pumping system P; gearing connecting the motor M to the driving axle of the automobile; a clutch K 20 for disconnecting the motor M from the driving gearing and connecting said gearing directly to the engine E; and various controlling devices for the engine, pumps, and motors. The prime mover E may be a 25 gasoline engine of any approved make, but is preferably a high speed engine, as the latter is light in weight, and is also best adapted for operating the pumps herein shown. The pumping mechanism comprises a horizontally disposed casing 1, in which is 30 mounted a series of rotary pumps a, b, c, d, e and f. These pumps are all alike, and each comprises two pairs of right and left handed intermeshing screws adapted, when rotated, to pump a liquid from the outer ends 35 of the pump in toward the center. As herein shown the rotary members of the pumps are carried by parallel shafts 3, 4, 5 and 6. On the shafts 3 and 4 are secured intermeshing gears 7 and 8. Similar gears 9 and 40 10 are secured to the shafts 5 and 6. The shafts 4 and 5 are extended to receive gears 12 and 13. The shaft 11 of the engine E extends through the casing 1, and is provided with journaled bearings therein. Secured to the engine shaft 11 is a driving gear 14 which meshes with the gears 12 and 13. It will thus be seen that when the shaft 11 is rotated the pumps will be operated by 45 means of the gearing just described. Within the casing 1 are journaled two parallel cylindrical valves 15 and 16 which are adapted to connect the pumps either in parallel or in series, or to form various parallel-series combinations of the pumps. The left hand ends of the valve stems extend beyond the casing and have secured thereto the intermeshing gear wheels 17 and 18. The gear wheel 17 is in mesh with the mutilated gear wheel 19 keyed to a shaft 20.

A bevel gear wheel 21 also secured to the shaft 20 meshes with a bevel pinion 22 on the rear end of a shaft 23 which extends forward to the steering mechanism.

The steering mechanism may be of the usual, or any approved construction, and as herein shown comprises the steering wheel 24 on the upper end of the steering shaft 25 which extends downwardly through a casing 26. Mounted in the casing 26 and surrounding the shaft 25 is a sleeve 27, the upper end of which is enlarged and provided with a pointer 28 adapted to move over a scale 29 formed on the flanged end 30 of the casing 26. A controlling lever 31 is secured to the upper end of the sleeve 27. The lower end of the latter is provided with a gear 32 in mesh with a pinion 33 on the forward end of the shaft 23.

The pumping mechanism P is adapted to force a liquid such as water or oil, but preferably a light oil, from the pressure chamber 34 through a pipe 35 to the reversing valve R of the motors M; after circulating through the motors the liquid is returned through a pipe 36 to the exhaust chamber 37; from the latter it is again drawn into the pump. When the automobile has been stopped, and the engine E continues to operate the pumping mechanism, the circulation of the liquid is confined within the casing 1. The valves 15 and 16 are at this time in the position shown in Figs. 7 and 15. The liquid passes from the exhaust chamber 37 through a port 38 and by way of the annular recess or passage 39 in the valve 16 to the passage 40 communicating with the outer ends of the pump a. The operation of the latter draws liquid inwardly to the center of the pump and forces it through the port 41 in the valve casing 16', and through the passage 42 in the valve 16 to the passage 43, which communicates with the pump b, the latter pumps the liquid through the valve passage 44 to the pump c, which in turn forces the liquid through passages 45, 46 and 47 in the valve 16, casing 1, and valve 15, respectively, to the pump d, the latter pumps the liquid through the passage 48 to the pump e, and from thence the circulation continues through the passage 49, pump f, passage 50 in the valve 15, and port 51 into the chamber 37, which completes the circulation. The operation of the engine E, therefore, causes a circulation of the fluid through the pumps, but as there is little resistance to the circulating liquid, but little power is consumed.

When the controlling lever is moved to rotate the valves 15 and 16, they successively assume the positions shown in Figs. 16 to 20, inclusive. When they are in the position shown in Fig. 16, the circulation of the liquid is from the exhaust chamber 37, and through the pumps in series, as in Fig. 15,

except that the last pump *f* discharges through a passage 52 in the valve 15, and port 53, into the pressure chamber 34. From the pressure chamber the liquid circulates 5 through the motors M, effecting the operation of the latter, and is returned from thence to the exhaust chamber 37. As all the pumps are connected in series the quantity of liquid circulating is small, but a 10 high pressure is obtained, so that the motors M can operate with great power but at a slow speed. When the valves assume the position shown in Fig. 17, a parallel series combination of the pumps is effected. The 15 circulation from the exhaust chamber 37 and through the pumps *a*, *b* and *c* is the same as in Fig. 16, but the pump *c* discharges through a passage 53 in the valve 16 and the port 54 in the valve casing into the 20 pressure chamber 34. The passage 46 is at this time cut off by the valves. Liquid also circulates from the exhaust chamber directly through a passage 55 in the valve 15 to the pump *d*, and in series through the 25 pumps *d*, *e* and *f* to the pressure chamber as in Fig. 16. In Fig. 17, the two sets of pumps *a*, *b*, *c* and *d*, *e*, *f*, are arranged in parallel, so that double the quantity of liquid will be circulated, but at substantially 30 half the pressure obtained in the preceding arrangement.

In Fig. 18 the valves have reached a position in which the pumps *a* and *b* are arranged in series, and the pump *b* discharges 35 through a passage 56 into the pressure chamber. The pumps *c* and *d* are also in series, the circulation being from the exhaust chamber through a passage 57, pump *c*, passages 58, 46, 59, pump *d* and passage 40 60 to the pressure chamber. The pumps *e* and *f* are also in series, the pump *e* drawing directly from the exhaust chamber through the passage 61 in the valve 15. With this arrangement, the volume of liquid 45 circulated by the pumps will be three times that of Fig. 16, but with one-third the pressure. With the next position of the valves as shown in Fig. 19, the circulation of the liquid is directly from the exhaust chamber 50 through all the pumps in parallel to the pressure chamber. This arrangement supplies the greatest volume of liquid at the lowest pressure. The motors M can now operate at about six times the high pressure 55 speed, the torque being correspondingly reduced. The next position of the valves is shown in Fig. 20, and connects the pumps in series and confines the circulation to the pumps, the same as with the arrangement 60 shown in Fig. 15. The purpose of this last arrangement will be fully explained later. The motors M comprise two three-cylinder hydraulic or fluid motors, connected to form a unit. This construction as herein shown 65 is an improvement on the well-known type of six-cylinder Brotherhood engine. I prefer this type of engine as being well adapted to drive the machinery, and further, because the liquid in the engine may be used as a brake whenever necessary, as for example, 70 going down hill with an automobile truck. The two motors are of substantially the same construction so that the description of one will suffice for both. Each motor comprises three cylinders N, and pistons O. 75 The latter are connected by connecting rods 62 to the crank-pins 63 and cranks 64 connected to the motor shaft 65. A valve casing 66 in which the shaft 65 is journaled, is formed with arms 67 extending to the outer 80 ends of the cylinders and bolted to the latter. These arms 67 are provided with passages 68 establishing communication between the valve casing 66 and the outer ends of the cylinders N. Within the casing 66 is a rotary valve 69 keyed to the shaft 65. The valve 69 comprises an outer flange 70, an inner flange 71, and a diagonally disposed flange member 72 located between the flanges 70 and 71. The passages 68 open 85 into the valve casing about midway between the flanges 70 and 71, so that as the valve rotates the flange 72 will extend alternately on opposite sides of each passage 68. The flow of the liquid to and from the motors is 90 by way of pipes 73 and 74. These pipes, as shown in Fig. 13, communicate with the ports 75 and 76, located respectively adjacent the flanges 70 and 71. The pipes 73 and 74 are connected respectively by pipes 100 77 and 78 to the valve chamber 79 of the reversing valve R (see Fig. 14). With the reversing valve in the position shown, the liquid from the pressure pipe 35 circulates 105 around the valve and through the pipes 77 and 73 to the port 75 at the left hand side of the flange 72, Fig. 13. From thence it passes through the passage 68, as indicated by the arrow, Fig. 13, into the motor cylinder N to operate the piston O. The ports 110 are so arranged that each piston O is moving inwardly while its cylinder is in communication with the pressure supply as just described. As the piston reaches its inner position, the flange 72 is moved past the corresponding passage 68 to bring the latter in communication with the exhaust pipe 74, and thereby permit the return movement of the piston, the liquid being forced from the cylinder through the passage 68, valve-casing 66, port 76, pipes 74 and 78, into the reversing valve chamber 79, and from thence through the pipe 36 to the exhaust chamber 37. To reverse the hydraulic motors, the 115 valve R is moved to the left. This cuts off the flow of liquid from the pressure pipe 35 to the pipe 77, and puts the latter in communication with the exhaust pipe 36, through the hollow valve R. The pressure pipe 35 is now in communication 120 125 130

from the pipe 35 around a reduced portion of the pipe 35 around a reduced portion of the valve R, to the pipe 78. This reversal of the valve R therefore effects 5 the operation of the motors M in the reverse direction.

The gearing between the motors M and the driving axle of the automobile and including the clutch mechanism will now be 10 described. Referring to Figs. 5 and 6, it will be seen that the shaft 65 of the motor M has keyed thereto one member 80 of a friction clutch K'. This member is in the form 15 of a disk provided with a flange within which is located the other member 81 of the clutch. The latter comprises a hub 83 keyed to a sleeve 82 loosely mounted on the shaft 65, and extending into the clutch member 80. The hub 83 is formed with an ex- 20 tension 84 and arms 85 and 86, which form a friction surface adapted to engage the inner surface of the clutch member 80. The free ends of the arms 85 and 86 are connected by a rod 87 having right and left 25 hand screw threads on its opposite ends engaging correspondingly threaded recesses in the arms 85 and 86. The rod 87 has keyed thereto an arm 88 by which the rod may be rotated. A slight rotation of the rod in one 30 direction serves to separate the arms 85 and 86 sufficiently to clutch the member 80; while a slight rotation in the reverse direction draws the arms toward each other and releases the clutch members so that they may 35 be rotated independently of each other. A clutch K² similar to the one just described comprises a clutch member 89 loosely mounted on the sleeve 82 and an inner clutch member 90 keyed to the sleeve 82. The member 40 90 is operated by means of an arm 91 corresponding to the arm 88. A sleeve 92 is splined on the sleeve 82 so as to be slidable longitudinally thereof, but preventing independent rotation of the sleeves. The sleeve 45 92 is connected to the arms 88 and 91 by means of links 93 and 94, and is provided with an annular recess 95. A bell-crank lever 96, pivoted at 97, has one arm bifurcated and provided with extensions engaging 50 the recess 95. When the bell-crank lever is rotated about its pivot to move the sleeve 92 to the left, the link 93 pulls the arm 88 downward and rotates the rod 87 in a direction to release the clutch K'. At the same 55 time the link 94 rotates the arm 91 so as to engage the members of the clutch K². The clutch member 89 is provided with sprocket teeth 98 to form a sprocket wheel which is connected by a sprocket chain 99 extending 60 around the sprocket pinion 100 secured to the end of the engine shaft 11. The sleeve 82 is formed at its outer end with a sprocket wheel 101 connected by the chain 102 with a driving member 103 extending to the gear

box 104 of the driving axle of the automobile.

Referring to Fig. 9, the mutilated gear wheel 19 is formed with a smooth arc-shaped surface 105 forming about one-half the periphery of the gear wheel. A gear wheel 106, 70 provided with gear teeth 107, is formed with an interlocking surface 108 engaging the surface 105, and serving to hold the gear 106 stationary, while the surfaces 105 and 108 are in contact. The gear wheel 17 is provided with an arc-shaped surface 109, also 75 adapted to engage the surface 105 and interlock the gears 17 and 19. The gear wheel 106 is connected by a link 110 with a horizontal rod 111. The latter is connected at 80 one end to the bell-crank lever 96 as shown in Fig. 1. The opposite end of the rod 111 is connected to one arm of a bell-crank lever 112 pivoted at 113. A horizontal rod 114 is connected at its rear end to the bell-crank 85 lever 112, and extends forward to a bracket 115, in which it is slidably mounted. Fuel is supplied to the engine E through the carburetor C and pipes 116 and 117, leading to the combustion chambers of the engine. The 90 quantity of fuel supplied is regulated by means of the valve V; the latter is provided with a valve stem 118, having its free end slidably mounted in the bracket 115. A centrifugal speed governor G, which may be of 95 the usual or any preferred construction, is connected to a shaft 119 geared in any suitable way to the engine E, so as to rotate with a speed proportional to that of the engine. This governor carries a disk 120, 100 the periphery of which extends between two flange members 121 and 122 of a valve shifter 123 keyed to the shaft 118. The governor in a well understood manner causes the valve V to shift in accordance with variations in speed of the engine, and is so adjusted that it will normally permit the engine to run at nearly full speed. On the end of the rod 114 is a stopping device 124 located between the bracket 115 and the 110 member 121 and serving to prevent the valve V from being entirely closed. Thus when the speed of the engine becomes sufficient to draw the disk 120 back to the position shown in Fig. 3, the stop 124 prevents a further 115 closing of the valve. The rod 114 is also used to move the valve V, as will be explained later. Still another means for operating the valve V consists in a foot lever 125 connected by a link 126 to a bell-crank 120 lever 127, pivoted at 128, and having an arm 129 extending downward into engagement with the valve shifter 123. The bell-crank lever 127 has a lost motion connection with the rod 126, permitting the valve V to be 125 shifted into open position without moving the link 126, but permitting the latter to positively operate the valve whenever it is

so desired. A foot lever 130 for operating the reversing valve R is connected by a rod 131 to the reversing valve rod 132.

The operation of the mechanism thus far described will be understood from the following: Assuming the controlling lever 31 to be in the "off" position as shown, and the gasoline engine E to be running, the pumping mechanism P will be operated as already described, to cause a circulation of the oil, or other liquid, within the pump casing, the valves 15 and 16 being in the position shown in Figs. 7 and 15. The engine shaft 11 also operates the sprocket chain 99 and rotates the member 89 of the clutch K². As the sleeve 92 is in its right hand position at this time, and the members of the clutch K² are disconnected, the member 89 will rotate idly on the sleeve 82. There is therefore no power transmitted either to the motors M or to the driving mechanism extending to the driving axle. To start the machine, the operator moves the controlling lever 31 to the right to bring the pointer 28 opposite the first scale marking. This movement of the controller operates through the mechanism already described to rotate the gears shown in Fig. 9, and bring the valves 15 and 16 into the position shown in Fig. 16. This connects the pumps with the motors M, the pumps being in series and the liquid is supplied to the motors at a comparatively high pressure, so that the latter can operate with a powerful torque to start the machine. At this time the members of the clutch K' are connected so that the motor shaft 65 operates through the clutch members 80 and 81 to rotate the sleeve 82, and the sprocket wheel 101. The latter drives a train of gearing 102 and 103, etc., to drive the automobile. The machine runs at slow speed on account of the small volume of liquid being circulated through the pumps and motors. As the controlling lever is moved step by step to the right, the valves successively assume the positions shown in Figs. 17, 18 and 19, and thereby gradually increase the volume of liquid supplied to the motors, and thereby increase the speed of the latter. Referring again to Fig. 9, it will be seen that the rotation of the gear wheel 19 during this time to operate the valves had no effect on the gear wheel 106, but has moved the teeth of the gear 19, as indicated by the arrow, toward the teeth 107 on the gear 106. The next step in the rotation of the gear wheel 19 brings the valves 15 and 16 into the position shown in Fig. 20, and thereby cuts off the supply of liquid to the motors M as previously described, and at the same time rotates the gear wheel 106, as the teeth on the gear 19 have by this time been brought into mesh with the teeth 107. The rotation of

the gear 106 operates through the link 110 to rotate the bell-crank lever 96, and shift the clutch sleeve 92 to the left. This operates to release the clutch members 80 and 81, so that the rotation of the shaft 65 is not transmitted to the sprocket wheel 101, thus the motors M are disconnected from the driving mechanism. The movement of the sleeve 92 to the left also connects the members of the clutch K². The engine E therefore is connected through the chain 99 and clutch K² to the sprocket wheel 101, and therefore operates to drive the machine directly. When the valves 15 and 16 have been brought to the position of Fig. 20, interlocking surfaces 109 and 105 of the gears 17 and 19 are brought together and prevent further rotation of the gears 17 and 18, so that the valves remain stationary during any further movement of the gears 19 and 106. The rotation of the gear 106 not only serves to shift the clutch mechanism and connect the engine directly with the driving axle, but operates through the rod 111, bell-crank 112 and rod 114 to control the valve V. If it is desired to increase the speed after the controlling lever has been moved to operate the clutch, the lever is moved still further, thereby pushing the rod 114 forward carrying the valve V forward and increasing the supply of fuel to the engine. It will be noted that this enables the valve to be opened in opposition to the action of the governor when the machine is running at a high speed. The governor normally operates to regulate the admission of fuel to the engine and allow the same to run at nearly full speed and horse-power, while the engine is connected to the fluid motors and operating through them to drive the machinery. The connections between the controlling lever and valve V enable the power of the engine to be increased and the speed of the machine accelerated after the engine has been disconnected from the hydraulic motors. This manual control of the supply of fuel to the engine is therefore in conjunction with the control of the hydraulic system, although the speed may be varied and controlled after the hydraulic motors are disconnected. The foot lever 125 and the connections to the valve V form a means for manually controlling the horse-power output of the engine, both while the motors M are operating, and while they are disconnected. If, for example, at any time the motors M are found insufficient to start the automobile, or to operate the same, for example in going up a steep hill, the foot lever 25 may be depressed to open the valve V wider, and thereby increase the power of the engine.

The hydraulic transmission mechanism is intended especially for use in starting and

stopping the machine and operating it at intermediate speeds. The clutch mechanism is provided in order that the machine may be driven directly from the engine as much of the time as practicable, as it is well known in all kinds of transmission gears there is some loss of power in operating the same. It will be understood that if the clutch device herein shown should at any time get out of order, it would not prevent the operation of the machine, because it can be run without the use of the clutch mechanism. An air chamber 140 is connected by a pipe 141 to the pressure chamber of the pumping system. This air chamber acts in the usual way as a trap for any air bubbles that may get into the circulating liquid, and also acts as a cushion device to prevent any sudden variations in the pressure of the liquid. A relief valve 142 opens from the pressure chamber 34 to the discharge chamber 37 to prevent any excessive rise in pressure. The tension of the spring 143 surrounding the valve stem is so adjusted that the valve will open when the pressure in the chamber 34 exceeds a predetermined limit. The style of pumps used in the present system of power transmission may be varied if desired. I prefer, however, to use a rotary pump or pumps, because they can be operated at high speed. High speed pumps are suitable to the type of engine best adapted for automobiles, that is, a high speed engine which may be made both very powerful and very light in weight. Reciprocating pumps however may be used, if in any case it shall be found that they have any advantage over other forms.

In Figs. 21, 22 and 23, is shown another well-known type of rotary pumps. As here shown six pumps are connected to be driven by the engine shaft 11. Each pump comprises a gear wheel or member 145 keyed to the engine shaft, and driving a corresponding gear 146. Each pump is provided with a separate compartment in the casing 1^a. A pressure chamber 34^a and an exhaust chamber 37^a extend along opposite sides of the pumps; valves 15^a and 16^a, similar to the valves 15 and 16, Fig. 7 control the connections between the several pumps, and between the pumps and pressure chamber and exhaust chamber. The parts shown in Fig. 21 are in a position corresponding to Fig. 7. The arrows indicate the circulation of liquid through the pumps. In the position shown, the valve 15^a cuts off all communication between the pressure chamber and the pumps. The fluid is drawn from the exhaust chamber 37^a through an opening 147 in the valve 16^a, and forced through the first pump a', and from thence through a passage 148 to the intake side of the next pump b'. In like manner the circulation continues through the pumps c', d', e' and f'. From the pump

it continues through passage 149 in the valve 15^a, through a pipe 150 to the exhaust chamber 37^a, thus completing the circulation. As the valves 15^a and 16^a are rotated, the pumps are first connected in series with the motors M by way of the pipes 35 and 36, and may then be connected successively in the various combinations shown in Figs. 17 to 20. The gears 17' and 18' for operating the valves 15^a and 16^a are substantially like the gears 17 and 18 of Fig. 19. In the present instance, however, an idler gear 151 is placed between the gears 17' and 18' owing to the greater distance between the valves. This of course changes the direction of rotation for the valve 16^a and the passage in the latter may be positioned to effect the same results in the operation of the valve.

Figs. 24, 25 and 26 illustrate still another form of rotary pumps. In this instance centrifugal pumps are used. These centrifugal pumps a², b², c², d², e², and f², are keyed as usual to the engine shaft 11. When the liquid enters each pump at the intake 152 at the center of the pump it is thrown by centrifugal force through the passages 153 to the annular passage 154 surrounding the rotary member of the pump. From thence the liquid can circulate through the passage 155 to the intake of the next succeeding pump. In this manner the liquid may flow from the exhaust chamber 37^b through the pumps in series, and by way of the pipe 156 back to the exhaust chamber. The rotary valves 15^b and 16^b are provided with passages so disposed that as the valves are rotated the pumps may be connected to the motors and various combinations obtained as in the other forms of pumps. The arrangement of gearing shown in Fig. 26 comprises two idler gears, 151^a and 151^b between the gears 17^a and 18^a, the latter gears corresponding to the gears 17 and 18 of Fig. 9. I have shown three styles of rotary pumps and valves adapted to effect the proper communications and combinations of these pumps, but it will be understood that other styles of pumps and also variations in the forms of valves may be employed. I therefore do not wish to be limited to the particular combinations shown. The principal object in the arrangement of the pumps and valves is to enable more than two speeds to be obtained as it is desirable to have at least four or more different speeds. The pumping mechanism is preferably arranged so that when the oil is not used for driving the fluid motors, it will pass through the pumps with but little pressure. In this way the moving parts of the pumps are always kept well lubricated. The gearing for connecting the engine shaft to drive the machine independently of the motors M is preferably so proportioned that the speed of the machine will be increased as the clutch 130

mechanism is operated to connect the engine directly with the driving axle of the machine. In other words, for a given speed of the engine, a greater speed is obtained when the engine is connected directly to the driving axle than when the power is transmitted through the pumping mechanism with the pump connected in parallel.

While I have shown the valves diagrammatically in order to clearly illustrate the principles of my invention, I may in practice make use of balanced valves in order to reduce to a minimum the power needed to operate the valves. I have omitted the illustration of balanced valves as they would only complicate the drawings and make them more difficult to understand.

In practice the speed mechanism will be made partly of steel and partly of aluminum when it is intended for use with automobiles, as it is important in such cases to reduce the weight of the machinery as much as possible.

The present invention is adapted for various uses, such as operating winding drums for elevators, for use on railway trains, with various types of prime movers, in power installations, etc.

I wish not to be limited to the particular forms of controlling levers and other controlling mechanism shown, as the same may be arranged in many different ways.

Various changes in many of the details of construction and arrangements of parts might obviously be made without departing from the spirit and scope of the invention. I wish therefore not to be limited to the particular construction herein set forth.

What I claim as new and desire to secure by Letters Patent is:—

1. The combination with pumping mechanism, of a fluid motor, means for conveying fluid under pressure from the pumping mechanism to the motor, and means for varying the arrangement of the pumping mechanism as by series and parallel working to vary the volume and pressure of fluid delivered thereby, the pressure varying from a maximum to a minimum in a plurality of steps.

2. The combination with pumping mechanism comprising a plurality of pumps, of a fluid motor, means for conveying fluid under pressure from the pumps to the motor, and means to vary the connections among the pumps to effect a variation in the volume and pressure of fluid delivered to the motor, the pressure varying from a maximum to a minimum in a plurality of steps.

3. The combination with a fluid motor, of a plurality of pumps, a plurality of passages connecting the several pumps with each other and with the motor, and means for varying the arrangement of said passages in successive steps to effect a gradual variation in the volume and pressure of fluid delivered

from the pumps to the motor, the pressure varying from a maximum to a minimum in a plurality of steps.

4. The combination with a fluid motor, of a plurality of pumps, passages for conveying fluid between the several pumps and between the pumps and the motor, and valve mechanism operable to vary the arrangement of said passages and thereby vary the pressure and volume of liquid delivered to the motor, the pressure varying from a maximum to a minimum in a plurality of steps.

5. The combination with a fluid motor, of a plurality of pumps, means for conveying fluid from the pumps to the motor, and means for varying the communications between the pumps in successive steps from a parallel to a multiple series and series communication, or vice versa.

6. The combination with a fluid motor, of a plurality of pumps, communicating passages between the several pumps and between the pumps and the motor, and means for varying the arrangement of said passages to effect the flow of the fluid through the pumps in series, in multiple series, and in multiple, successively.

7. The combination with a fluid motor, of a plurality of pumps, communicating passages between the several pumps and between the pumps and the motor, valves controlling said passages, and operable to connect the pumps in series, in multiple series, and in multiple, successively.

8. The combination with a fluid motor, of a plurality of pumps, communicating passages between the several pumps and between the pumps and the motor, means for varying the arrangement of said passages to connect the pumps all in series or in two parallel sets, with the pumps of each set connected in series, or in more than two parallel sets with the pumps of each set in series, or with all the pumps connected in parallel.

9. The combination with a fluid motor, of a pressure chamber, means for conveying fluid from the pressure chamber to the motor, a discharge chamber, means for conveying the fluid from the motor to the discharge chamber, a plurality of pumps communicating with said chambers and with each other, and means to vary the arrangement of the communicating passages to connect the pumps either in series, in parallel series, or in multiple, between said chambers.

10. The combination with a plurality of pumps, of a fluid operated reciprocating motor having a plurality of cylinders, means for conveying a fluid from the pumps to the motor, and means associated with the pumps for effecting the flow of fluid through the pumps, either in multiple, in multiple series or in series, and thereby varying the pressure and volume of fluid delivered to the mo-

tor to vary the speed and torque of the latter.

11. The combination with a plurality of pumps, of a fluid motor, means for conveying fluid from the pumps to the motor, and means to effect the delivery of fluid by the pumps, either in multiple under a minimum pressure, or in series with a maximum pressure, or in multiple series in a plurality of 10 steps with the pressure corresponding to the volume of fluid delivered by the pumps.

12. The combination with a plurality of rotary pumps, means for driving the same at a uniform speed, a hydraulic motor, a 15 shaft member rotated thereby, means for conveying fluid from the pumps to the motor, controlling mechanism to connect the pumps in multiple whereby the fluid will be delivered at a minimum pressure, and to connect 20 the pumps in series whereby the fluid will be delivered at a maximum pressure, and in multiple series to obtain an intermediate pressure.

13. The combination with a plurality of 25 pumps, of a hydraulic motor, means for delivering fluid from the pumps to the motor, and controlling means to effect the operation of the pumps in multiple with a minimum fluid pressure, in series with a maximum fluid pressure, and in multiple series 30 with a fluid pressure between a maximum and a minimum.

14. The combination with a plurality of 35 pumps, of a reciprocating multiple cylinder motor, means to convey fluid from the pumps to the motor, means to direct the fluid through the pumps in multiple, means to direct the fluid through the pumps in multiple series, in a plurality of steps, and means 40 to direct the fluid through all the pumps in series.

15. The combination with a fluid motor 45 operable to produce a rotary motion, of a plurality of pumps arranged to be connected in series, series parallel and parallel, controlling mechanism for the pumps, operable to produce an increase or decrease in the pressure of the fluid delivered by the pump in a plurality of steps, the pressure varying 50 from a maximum to a minimum, or vice versa.

16. The combination with a fluid motor 55 adapted to produce a rotary motion, of a plurality of pumps, means for conveying fluid from the pumps to the motor, and controlling means operable to vary the quantity of fluid delivered by the pumps from a minimum to a maximum or vice versa by connecting the pumps in series, series parallel and parallel.

17. The combination with a fluid motor, 60 of a plurality of pumps for pumping a fluid, means for conveying the fluid to the motor, and controlling mechanism operable to connect the pumps in series, series parallel

and parallel to effect a pumping of the fluid at a high pressure and small volume, or at a low pressure and large volume.

18. The combination with a fluid motor, 65 of a plurality of pumps, means for conveying fluid from the pumps to the motor, means for directing the fluid through the pumps, either in series, in multiple series, in a plurality of steps, or in multiple, and thereby 70 securing a variation in the volume and pressure of the liquid, and a reversing valve for 75 the motor controlling the direction of rotation of the motor.

19. The combination with an internal 80 combustion engine, of a plurality of pumps, driving connections between the engine and pumps, a fluid motor, means for conveying fluid from the pumps to the motor, and variable means for directing the flow of fluid through the pumps in series, series 85 multiple and parallel to secure a variation in the volume and pressure of the fluid delivered to the motor.

20. The combination with an internal 90 combustion engine, of a plurality of pumps connected to be driven thereby, a fluid motor associated with the pumps, and means 95 for connecting the pumps in series, series multiple and parallel for effecting a variation in the quantity and pressure of fluid delivered by the pumps without varying the speed or horse-power output of the engine.

21. The combination with an internal 100 combustion engine, of a plurality of pumps operatively connected thereto, a fluid motor, means for conveying fluid under pressure 105 from the pumps to the motor, and means for connecting the pumps in series, multiple series, and multiple so as to vary the volume and pressure of fluid delivered by the pumps, in a plurality of successive steps without varying the speed of the pumps.

22. The combination with an internal 110 combustion engine, of a plurality of pumps driven thereby, variable means for directing the flow of a fluid through the pumps either in multiple, multiple series, or in series 115 to secure a large quantity at low pressure, or a small quantity at high pressure, and automatic means for governing the speed of the engine.

23. The combination with an internal 120 combustion engine, of a plurality of pumps driven thereby, controlling means to direct the flow of fluid through the pumps either in 125 multiple, in multiple series, or in series, successively, or vice versa, a motor adapted to be operated by fluid pressure from the pumps and means to automatically govern the horse-power output of the engine.

24. The combination with an internal 130 combustion engine, of a series of pumps driven thereby, controlling means for directing the flow of fluid through all the pumps in multiple, or in multiple series in a plurality of

steps, or through all the pumps in series, a motor adapted to be operated by fluid pressure from the pumps and automatic means for governing the speed of the engine and 5 coöperating with said controlling means and operative to maintain the speed of the engine practically constant.

25. The combination with an internal combustion engine, of a plurality of pumps driven thereby, controlling means for directing the flow of fluid through the pumps, either in multiple, or in multiple series, or in series, means to automatically maintain the speed of the engine substantially constant, a motor adapted to be operated by 10 fluid pressure from the pumps and additional means operable manually to increase the speed of the engine.

26. The combination with an internal combustion engine, of a plurality of pumps connected to be driven thereby, controlling means to effect a variation in the volume and pressure of the fluid conveyed through the pumps by connecting the pumps in series, 25 series parallel or parallel, means to automatically govern the supply of fuel to the engine to maintain the same at a practically constant speed, and a motor adapted to be operated by fluid from said pumps.

30. 27. The combination with an internal combustion engine, of means for automatically governing the speed of the engine, a pumping system connected to be driven by the engine and comprising a plurality of 35 pumping units, and means for directing the flow of fluid through said pumping units either in series, series parallel or in parallel, and a motor operated by fluid from said pumping system.

40. 28. The combination with an internal combustion engine, of a plurality of pumps, mechanism operated by fluid pressure supplied by the pumps, communicating passages connecting the pumps and said mechanism, 45 and means for varying the arrangement of said passages to effect the flow of fluid through said pumps either in parallel, in series multiple, or in series to said mechanism or through the pumps independent of said 50 mechanism.

29. The combination with pumping mechanism comprising a plurality of pumps, of means for driving the pumps, means for directing the flow of fluid through the pumps 55 either in multiple, in multiple series, or in series, mechanism operated by said fluid, and means for directing the circulation of the fluid through the pumps independently of said operated mechanism.

60. 30. The combination with a plurality of pumps, of mechanism adapted to be operated by fluid pressure from said pumps, a pressure chamber and an exhaust chamber communicating with said mechanism, communicating 65 passages between the pumps, and

between the pressure and exhaust chambers and the pumps, means for varying said passages to connect the pumps with said mechanism either in parallel, in multiple series, or in series, or to effect a circulation of fluid 70 through the pumps independently of said mechanism.

31. In power transmitting mechanism, the combination with a fluid motor, of a shaft connected thereto for rotation, a plurality of pumps, a pressure chamber communicating with the pumps, communicating 75 passages between the pumps, means for varying the arrangement of said passages to connect the pumps either in series, multiple series, or multiple, to effect a corresponding 80 variation in the pressure and volume of fluid transmitted from the pumps to the pressure chamber, and means for conveying the fluid from the pressure chamber to said fluid motor.

32. In power transmitting mechanism, the combination with a fluid motor, of a plurality of pumps, a pressure chamber and an exhaust chamber, communicating 85 passages between the pumps and between the latter and the pressure and exhaust chambers, means for varying the arrangement of said 90 passages to convey fluid from the exhaust chamber to the pressure chamber, through the pumps, either in multiple, or in multiple 95 series, or in series, means to convey the fluid from the pressure chamber to the motor, and means to return the fluid from the motor to the exhaust chamber.

33. The combination in power transmitting mechanism, of a prime mover, a plurality of pumping devices connected thereto, a fluid motor, means for directing fluid through said pumping devices either in multiple, in multiple series, or in series, and 100 means for conveying said fluid from the pumping devices to the fluid motor.

34. In fluid power transmission mechanism, the combination with a fluid motor, of a plurality of pumps, an internal combustion engine connected to operate the pumps, valve mechanism, ports and passages formed in the pump casings and valve mechanism, means for operating the valve mechanism 110 and thereby varying the connections between the pumps from a series to a series-parallel and parallel relation to effect a discharge of fluid from the pumps either at a high pressure or a low pressure with a corresponding variation in the volume of fluid discharged, and means for conveying the fluid from the pumps to said motor.

35. In power transmission mechanism, the combination with a fluid motor, of a plurality of pumping devices, a prime mover connected to said devices, communicating 115 passages extending between said pumping devices, means for varying the arrangement of said passages to connect said pumping 120 devices, and means for conveying the fluid from the pumps to said motor.

devices either in multiple or in multiple series or in series, and thereby vary the speed and torque of the fluid motor, and means for conveying fluid from the pumping devices to the motor.

36. In fluid power transmission mechanism, the combination with a prime mover, of pumping mechanism comprising a plurality of pumps, a fluid motor, means for conveying fluid from the pumping mechanism to said motor, and controlling means associated with said pumping mechanism and operable to effect a variation in the pressure of the fluid discharged from the pumping mechanism from a maximum to a minimum with a corresponding variation in the volume of fluid delivered from a minimum to a maximum by connecting the pumps for series, parallel and multiple series working, so that the motor may be operated at a slow speed and with a high torque, and the speed gradually increased and the torque correspondingly decreased.

37. In a fluid power transmission system, the combination with an internal combustion engine, of a plurality of pumps, a fluid motor, means for conveying fluid from the pumps to the motor, valves associated with said pumps and formed with passages for conveying fluid, ports between said passages and the pumps, and means for operating the valves and thereby securing a variation in the connections between the pumps from a series connection to a series parallel and parallel connection, and thus obtaining a variation in the pressure and volume of fluid transmitted from the pumps to the motor.

38. In fluid power transmission mechanism, the combination with an internal combustion engine, of a fluid motor, pumping mechanism, a pressure chamber, means for conveying fluid from the pressure chamber to the motor, an exhaust chamber, means for conveying fluid from the motor to the exhaust chamber, valves associated with the pumping mechanism and formed with passages for conveying fluid, ports and passages adapted to connect the pumps with said passages in the valves, ports adapted to connect the pressure chamber and the exhaust chamber with passages in the valves, and means for operating the valves to vary the arrangement of said passages and ports to successively connect the pumps with the pressure and exhaust chambers, either in multiple, or multiple series, in a number of steps, or in series, or vice versa, thereby effecting a corresponding variation in the pressure and volume of fluid transmitted from the pressure chamber to the motor.

39. In fluid power transmission mechanism, the combination with a prime mover, of pumping mechanism, a fluid motor, means for conveying fluid from the pump-

ing mechanism to the motor to operate the latter, means for returning the fluid from the motor to the pumping mechanism, mechanism connected to the motor to be driven thereby, valves, ports and passages for establishing communication between the several pumps in series, series parallel and parallel, and between the pumps and the passages leading to the motor, and means for operating the valves to vary the arrangement of said passages and thereby effect a variation in the pressure and volume of fluid delivered to the motor, said valves being operable also into position to cut off the flow of liquid to the motor and direct its circulation through the pumping mechanism.

40. In fluid transmission mechanism, the combination with a prime mover, of pumping mechanism connected thereto comprising a plurality of pumps, a fluid motor associated with the pumping mechanism, means for varying the quantity and pressure of fluid transmitted from the pumps to the motor by connecting the pumps in series, series parallel and parallel relation, and automatic means to maintain the speed of the prime mover substantially constant during such variations.

41. The combination with a prime mover, of a pump connected thereto, a fluid motor adapted to be operated by fluid from the pump, an element connected to the motor to be driven thereby, means for connecting said driven element to the prime mover, and a single controlling device operable to disconnect the driven element from the motor and connect it directly to the prime mover, and at the same time increase the speed of the driven mechanism.

42. The combination with a prime mover, of a motor, means for driving the motor by power supplied from the prime mover, mechanism adapted to be driven by the motor, a clutch between said mechanism and the motor, a clutch between said mechanism and the prime mover, and a single device for operating said clutches to disconnect the motor from the driven mechanism and connect the latter directly to the prime mover, the direct connections being such as to effect an increase in the speed of the driven mechanism.

43. The combination with an internal combustion engine, of a pumping system driven thereby, a fluid motor associated with said system and operated by fluid supplied thereby, an element connected to said motor and operated thereby, and a device for disconnecting the motor from said driven element, and effecting a mechanical connection between said driven element and the engine, causing an increase in the speed of said driven element.

44. The combination with an internal

- combustion engine, of pumping mechanism, a fluid motor associated therewith, a driven element connected to the motor, means for increasing the speed of the engine, and a single device operable to effect a disconnection of the driven element from the motor, and a direct connection of said element to the engine, and operate said speed increasing means after said direct connection.
- 10 45. The combination with an internal combustion engine, of pumping mechanism connected thereto, a fluid motor, means for conveying fluid from the pumping mechanism to the motor to operate the latter, means for varying said pumping mechanism to effect a gradual variation in the speed of the motor, a driven element connected to the motor, means for disconnecting said driven element from the motor and effecting a connection between said element and
- 15 the engine resulting in an increased speed of said element for a given speed of the engine, a speed governor for the engine, and a manual device operable to effect a gradual increase in the speed of the driven element in 25 the following successive steps: first, effecting said variation in the pumping mechanism to gradually increase the speed of the motor, second, disconnecting said driven element from the motor and connecting it to 30 the engine, and third, effecting an increase in the speed of the engine.
- 20 In testimony whereof, I have signed my name to this specification in the presence of two subscribing witnesses.

AUGUST SUNDH.
